COMBINED TOY TRACKWAY AND SUPPORT SECTION

John R. Tilli, 4423 Meridian St., Philadelphia, Pa.

Filed June 2, 1958, Ser. No. 51,163

Term of patent 3½ years

(Cl. D34—15)

FIG. 1.

FIG. 2.

FIG. 3.

Fig. 1 is an exploded perspective view of a combined toy trackway and support section showing my new design;

Fig. 2 is a reduced side elevational view thereof with a portion shown fragmentarily for convenience of illustration; and

Fig. 3 is a reduced front elevational view.

I claim:

The ornamental design for a combined toy trackway and support section, substantially as shown and described.
